UNITED STATES PATENT OFFICE.

WILFRED JONES WHITE, OF DETROIT, MICHIGAN.

TRAFFIC WARNING DEVICE.

Application filed August 18, 1926. Serial No. 130,035.

The object of this invention is to provide a device to be attached to any element forming part of a load carried by a motor truck or the like, when the load or a portion thereof projects beyond the body of the vehicle to an extent causing it to constitute a menace to traffic.

A further object is to provide a collapsible device which may readily be carried at all times by the operator, when not required for active use, and may be available at a moment's notice,—the article being specially constructed to maintain its shape and position, and being conspicuous and of such unusual character that it cannot fail to be observed.

A further object is to provide an article of this kind which shall include a plurality of elements foldable with reference to a central member, and retained in extended position by particular locking devices.

With the foregoing and other objects in view, the invention consists in the novel construction and arrangement of elements described, illustrated and claimed, it being understood that modifications may be made within the scope of the claims without departing from the spirit of the invention.

In the drawings forming part of this application,

Figure 1 is a perspective view of the device, as it appears in use, the view showing a portion of a load, and a projecting timber or the like.

Figures 2 and 3 are views in elevation showing the device as it appears at different stages during the collapsing operation.

Figure 4 is a fragmentary view showing especially the locking or retaining device or devices.

Figure 5 is a further view of the locking means.

Figure 6 is a section on line 6—6 of Figure 4.

A disk 10 constitutes the central element of the device, and a semi-circular element 11 is connected by means of hinges 12 with the disk and is movable from a position approximately parallel therewith, when folded, to a position perpendicular with reference to the disk 10.

Separate wings 13 are connected with disk 10 by means of fingers such as 13', and these elements 13 have their inner edges spaced, and a U-member such as 14 has its opposite portions or leg portions connected respec-

tively with the elements 13, by means of rivets or otherwise, the U-element projecting beyond the edges of plates 13 and serving to mount a locking device.

The retaining or locking device for wings 13 include a curved or semi-circular member 16 pivotally mounted at 17 on the central portion of the U-member, the element 16 including a stem or the like 16' thru which the pivot 17 extends. The locking device including portions 16 and 16', is also of U-form, and includes a plate member having end portions cut to the configuration shown in Figures 4 and 5, the plate or strip of metal being bent over to form the U-portion, opposite side element being disposed on opposite sides of the element 14, as shown in Figure 6. The elements 16 also move on opposite sides of the wing members 13, and pass thru a slot 20 at the edge of semi-circular wing member 11, so that when in the position of Figure 4 the locking device retains the members 13 and the element 11 in the relative position shown in Figure 1, but when the locking device is moved to the position of Figure 5, the wings 13 will swing about their hinge connections, and may be moved into parallel relation with the disk 10, cutaway portion 16' facilitating this operation.

The hinge connections 12 for the semi-circular wing member 11 are so proportioned that said wing 11 may now be folded flat, so that the collapsible devices above the disk 10 will now assume the position assumed to exist at the close of the movement indicated in Figure 3.

A retaining pin 23 is passed thru registering apertures in the elements 14 and 16', when the parts are locked, and the cotter pin 24 connected with chain 25 provides additional securing means.

The device may be attached to a projecting element of the load, as shown conventionally in Figure 1, by any suitable means, but I have shown a flexible device 27, a loop member 28, a snap hook 29 and an element 30 adapted for engagement by the hook. A swivel connection permits of spinning movement.

The construction of the elements hingedly connected with the lower side of disk 10 is similar to that already described, in connection with elements 11 and 13, and in Figure 1 a portion of the semi-circular plate or wing is designated 11', and one of the

wings 13' is adapted to be positioned at a right angle with reference to plate or wing 11'. On the under side two of the wings 13' will be employed, and they are to be retained in a position perpendicular with reference to disk 10, by a locking device similar to that including elements or portions 16 and 16' of the pivoted locking device first described. The lower locking device as a whole is designated 35, and description of the details thereof appears to be unnecessary. The U-portion 36 of locking device 35 has connection with a loop member 37, and the latter is connected with a snap hook 38. In the present instance I have shown a weight 39 connected with the snap hook and adapted to retain the device in stable position, so far as necessary, it being understood that some degree of swinging movement will naturally result, and that this movement is desirable for the reason that it makes the signal or warning more conspicuous. The disk 10 and the various foldable elements are illustrated as being provided with circular portions 40, which are to be of any suitable character, being intended to act as aids to visibility either by day or by night. Moreover, the entire

device may be colored, with the same object in view.

Having described the invention what is claimed is:

1. A device of the class described, comprising a main plate, an element hinged to the main plate and movable from a position parallel therewith to a position at an angle with the plate, wings hinged to the plate on opposite sides of the hinged element first named, means for locking the hinged elements in a position at an angle with reference to each other, a U-shaped member connecting the wings and straddling said element hinged to the main plate, and means for pivotally mounting the locking means on the U-shaped member.

2. A warning device, comprising a main plate, elements hingedly connected with the plate and movable to angular position with reference to each other, and means for retaining said elements in angular relation, said means including a pivotally mounted device movable thru one of the hinged elements and alongside of the remaining hinged elements.

In testimony whereof I affix my signature.

WILFRED J. WHITE.
